UNITED STATES PATENT OFFICE.

JOHN P. WALSH, OF NEW YORK, N. Y., ASSIGNOR OF ONE-HALF TO HENRY J. McGUCKIN,
OF NEW YORK, N. Y.

HEADLIGHT FOR AUTOMOBILES AND THE LIKE.

1,152,676.

Specification of Letters Patent.

Patented Sept. 7, 1915.

Application filed June 17, 1914, Serial No. 845,637. Renewed August 2, 1915. Serial No. 43,340.

To all whom it may concern:

Be it known that I, JOHN P. WALSH, a citizen of the United States, residing at New York, in the county of New York and State of New York, have invented certain new and useful Improvements in Headlights for Automobiles and the like; and I do hereby declare the following to be a full, clear, and exact description of the invention, such 10 as will enable others skilled in the art to which it appertains to make and use the same.

This invention comprehends certain new and useful improvements in head-lights and 15 has for its primary object to provide a form of head-light which will be constructed in such manner that the usual glare will be eliminated and the head-light may be employed upon automobiles, motorcycles, ships, 20 or in fact wherever it is desired to use a head-light or any powerful reflected light.

This invention has for another object to provide a head-light of this character in 25 which the lens will be of improved construction and formed in such manner that a translucent liquid may be placed therein to soften the rays of light from the head-light and thereby do away with the blinding glare common with various forms of head-lights.

30 The invention has for another object to provide a head-light of this character in which the lens will be formed in such manner that it may be readily secured in position and the translucent liquid placed there- 35 in without removing said lens.

A further object of the invention is to provide improved and novel means for securing the hollow lens to the door of the head-light casing or body and forming an 40 airtight connection between said lens and door.

The invention has for a still further object to generally improve and simplify the construction of devices of this character and 45 increase the efficiency thereof without materially increasing the cost of the same.

With these and other objects in view as 50 will become more apparent as the description proceeds, the invention consists in certain novel features of construction, combination and arrangement of parts as will be hereinafter more fully described and claimed.

For a complete understanding of my in- 55 vention, reference is to be had to the follow-

ing description and accompanying drawings, in which—

Figure 1 is a perspective view of the complete device, Fig. 2 is an enlarged fragmentary perspective view of the clamping ring, 60 showing the upper portion thereof, and Fig. 3 is a transverse horizontal section of the lens.

Referring in detail to the drawings by numerals, 1 designates the body, 2 the lamp, 65 3 the reflector and 4 the door of a search light. The door 4 is secured in closed position by the usual hinge pins 9 removably engaged in the registering hinge eyes 10 carried by said body 1 and door 4. The 70 construction and arrangement of these parts, however, may be readily varied, as desired, as they do not constitute the most important part of my invention. I wish to call especial attention to the construction of the 75 lens and the manner in which the same is secured in position, however, as will now be clearly and fully described.

The lens 11 is held against the inner face of the front or main portion 8 of the door 4 80 along the central opening thereof, by means of the clamping ring 14 which is also secured to the inner face of the main or front portion 8 of the door 4 and has an offset portion 15 engaged over said flange 12 of 85 the lens 11 to securely fasten said lens 11 against the inner face of the door 4 and prevent movement of said lens. The lens 11 is also provided with a filling neck 16 which, when the lens 11 is in proper position, ex- 90 tends above the center of the door 4 whereby the hollow lens 11 may be readily filled with a translucent liquid of any desired color. The filling neck 16 is closed by a suitable cap 17 threaded upon its upper extremity and the securing ring 14 has an off- 95 set collar portion 18 at its upper side for engagement around the filling neck 16 in order that the main portion of the securing ring 14 may be retained in proper position. 100

By referring to Fig. 3, it will be readily seen that the hollow central or body portion of the lens 11 is of such form that the sides thereof have concentric convex surfaces and a solid peripheral flange is formed 105 around said hollow central or body portion of the lens and numbered 12, said flange being previously referred to and described with the function of said flange fully set forth. It will be understood, however, that 110

the shape of the body or central hollow portion of the lens, may be changed, if desired, and also the shape of the flange may be varied if deemed advisable.

5 Many minor changes in the details of construction, however, and arrangement of parts may be resorted to within the scope of the appended claim without departing from the spirit of the invention or sacrificing any of the advantages thereof.

10 What is claimed is:—

15 The combination with a door; of a lens positioned in said door and having a solid peripheral flange engaged against the inner face of said door, the central portion of said

lens being hollow and offset from the flange, the sides of the central portion of said lens having concentric convex surfaces, said lens having a filling opening communicating with the hollow central portion thereof, and 20 securing means carried by said door and engaged with said solid peripheral flange to retain said lens in position.

In testimony whereof I affix my signature in presence of two witnesses.

JOHN P. WALSH.
